(57) **CLAIM**

The ornamental design for a stage light, as shown and described.

DESCRIPTION

1. Stage light

1.1 : is a perspective view of our new design for a stage light.

1.2 : is a front view of 1.1.

1.3 : is a back view of 1.1.

1.4 : is a left view of 1.1.

1.5 : is a right view of 1.1.

1.6 : is a top view of 1.1.

1.7 : is a bottom view of 1.1.

The features shown in broken lines in the drawing depict environmental subject matter and form no part of the claimed design.

1 Claim, 7 Drawing Sheets(56)
